CLAIM

I claim the ornamental design for an underwear with protective pads, as shown and described.

DESCRIPTION

FIG. 1 is a perspective view of an underwear with protective pads showing my new design;

FIG. 2 is a front elevation view thereof;

FIG. 3 is a back elevation view thereof;

FIG. 4 is a left-side elevation view thereof;

FIG. 5 is a right-side elevation view thereof;

FIG. 6 is a top view thereof; and,

FIG. 7 is a bottom view thereof.

The broken lines illustrate stitching and are part of the claimed design.

1 Claim, 6 Drawing Sheets
